Inventor

J. G. Cattell

United States Patent Office.

L. C. CATELL, OF CLEVELAND, OHIO.

Letters Patent No. 97,879, dated December 14, 1869.

IMPROVED CAR-TANK COVER.

The Schedule referred to in these Letters Patent and making part of the same.

To all whom it may concern:

Be it known that I, L. C. CATELL, of Cleveland, in the county of Cuyahoga, and State of Ohio, have invented certain new and useful Improvements in a Car-Tank Man-Hole and Cover; and I do hereby declare that the following is a full and complete description of the same, reference being had to the accompanying drawings, making a part of this specification, in which—

Figure 1 is a plan view.

Figure 2 is a vertical section.

Like letters refer to like parts.

The nature of this invention relates to a car-tank man-hole and cover, constructed and arranged as hereinafter described.

In the drawings—

A represents the top of a tank, to which is secured the collar and rim B.

This collar is formed as shown in fig. 2, being provided with the rim that fits into the man-hole in the top of the tank A, and has a groove, a, in the lower part of which groove is a strip of leather packing, c, fig. 2, that extends round the entire length in the groove.

C is the cover, the under side of which is provided with a bead, b, that corresponds with and fits into the groove a, resting on the packing c.

This cover is also provided with lugs or projections c' at each side, which rest on the collar B.

Through these lugs pass the screws D D, that secure the cover in place, the screws being provided with double heads, shown in fig. 2, to which are attached chains E, the opposite end of the chain being secured to the top of the tank, the object of which is to prevent the screws from being lost.

The handle of the cover is also provided with a chain, I, secured to the tank, to prevent the cover being misplaced.

Under the edge of the collar, between that and the tank, is a small packing-cord, d, which is to prevent any escape of oil out past the rim, and between the collar and tank, the packing c, above referred to, making a tight and perfectly secure joint, preventing all escape of oil at that point.

What I claim as my improvement, and desire to secure by Letters Patent, is—

The collar B, provided with the groove a and packing-ring c, in combination with the cover C, having a bead, b, fitting the groove a, and the lugs c', all constructed and arranged to operate as and for the purpose set forth.
